[57] **CLAIM**

The ornamental design for an infrared communication port for a portable inkjet printer, as shown and described.

DESCRIPTION

FIG. 1 is a perspective view of an infrared communication port for a portable inkjet printer showing our new design;
 FIG. 2 is a left side elevational view thereof;
 FIG. 3 is a front elevational view thereof;
 FIG. 4 is a right side elevational view thereof;
 FIG. 5 is a rear elevational view thereof;
 FIG. 6 is a top plan view thereof; and,
 FIG. 7 is a bottom plan view thereof.

The broken lines in FIGS. 1 and 2 are for purposes of illustration only and form no part of the claimed design.
